UNITED STATES PATENT OFFICE.

JOHN S. VREDENBURGH, OF YONKERS, NEW YORK, ASSIGNOR TO ALEXANDER SMITH & SONS CARPET COMPANY, OF YONKERS, NEW YORK, A CORPORATION OF NEW YORK.

DESIGN FOR CARPET.

SPECIFICATION forming part of Design No. 35,635, dated January 28, 1902.

Application filed December 24, 1901. Serial No. 87,133. Term of patent 8½ years.

To all whom it may concern:

Be it known that I, JOHN S. VREDENBURGH, of Yonkers, county of Westchester, State of New York, have invented and produced a certain new and original Design for Carpets, fully described and represented in the following specification and the accompanying drawing, forming a part of the same.

The design is intended to be worked into or upon carpets or similar fabrics in such colors as may be desired; and I do hereby declare that the drawing accompanying this specification conveys to one skilled in the art of carpet weaving and manufacture a clear understanding of the same and is sufficient to enable such person to use my invention.

The design is characterized by the prominent scroll forms A, leaf and flower heads B, with leaf and flower-stem ornamentation C.

What I claim as new, and desire to secure by Letters Patent, is—

The design for carpet, substantially as shown and described.

In testimony whereof I have hereunto set my hand in the presence of two subscribing witnesses.

JOHN S. VREDENBURGH.
